United States Patent Office

Des. 188,657
Patented Aug. 23, 1960

188,657

CHAIR

Solomon Sigal, 125 Kensington St., Brooklyn, N.Y.

Filed Feb. 12, 1960, Ser. No. 59,365

Term of patent 7 years

(Cl. D15—1)

FIG. 1

FIG. 2

The characteristic features of my design reside in the portions shown by means of full lines in the drawing.

I claim:

The ornament design for a chair, as shown and described.
